UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

FEEDING MECHANISM FOR SEWING-MACHINES.

1,142,359.

Specification of Letters Patent.

Patented June 8, 1915.

Application filed January 4, 1908. Serial No. 409,287.

To all whom it may concern:

Be it known that I, LANSING ONDERDONK, a citizen of the United States, residing at New York city, in the county of New York, State of New York, have invented certain new and useful Improvements in Feeding Mechanism for Sewing-Machines, of which the following is a description, reference being had to the accompanying drawing, and 10 to the letters and figures of reference marked thereon.

My invention relates to sewing machines and more especially to feeding mechanisms for a blind stitch sewing machine, although 15 it is obvious that from certain aspects, my feeding mechanism may be used in connection with sewing machines of other types.

In the present embodiment of my invention, I have shown a blind stitch sewing machine comprising a work support, having a ridge forming member carried thereby, and an overhanging arm on which is supported the stitch forming mechanism and also the presser foot mechanism which includes two 25 presser feet bearing upon opposite sides of the ridge forming member.

In machines of this character, it is found that various disadvantages follow from using a four motion feed, which is moved 30 through the work support to engage the fabric in a vertical plane for the reason that the fabric is thereby crowded toward the apex of the ridge forming member.

After the fabric has been placed upon the 35 ridge forming member, and properly drawn over the same for the entrance of the needle, it is very desirable that the fabric be held in this stretched position across the apex of the ridge forming member.

The object of my invention is therefore, to 40 provide a feeding mechanism which shall cooperate with the presser members in such a manner as to engage and move the material without disturbing the stretched condition of 45 the material or crowding the same toward the stitching point.

A further object of my invention is to provide a plurality of feed dogs in connection 50 with an inclined work supporting member, which feed dogs are moved substantially at right angles to the work supporting members, through which they project to engage the fabric.

With these and other objects in view, my

invention consists in the parts and arrangements hereinafter shown, described and pointed out in the claims.

In the drawings, which show by way of illustration one embodiment of my invention; Figure 1 is a front elevation of the forward end of a sewing machine, with my improved feeding mechanism applied thereto, the work support being sectioned to show the feeding mechanism. Fig. 2 is an end elevation of the work support with the end cap removed. Fig. 3 is an end and side elevation of one of my improved feed dogs. Fig. 4 is an end and side elevation of the other feed dog. Fig. 5 is a sectional view through the forward end of the work support, showing a modified form of feeding mechanism. Fig. 6 is an end view of the same with the front plate removed. Fig. 7 is a detail view of my modified form of feed dog.

The work support 1 carries at its forward end a ridge forming member formed by the work supporting plates 2 and 3, which are secured thereto with their upper edges in contact so as to form a ridge extending 80 across the forward end of the work support 1. The overhanging arm 4, carries at its forward end suitable stitch forming mechanism which as shown, comprises a needle 5, mounted on a needle lever 6, pivoted at 7 to the overhanging arm. Coöperating with said needle is a looper 8. It is obvious that any other form of stitch forming mechanism may be substituted for that herein shown, without in any manner departing from the 90 spirit of my invention.

The presser mechanism for holding the material upon the work support, comprises a presser foot 9 which coöperates with the work supporting member 2, and a presser foot 10, which coöperates with the work supporting member 3. Said presser feet 9 and 10 are preferably pivoted to supporting levers 11 and 12 respectively, which are pivoted on the overhanging arm 4. Said presser feet 9 and 10 are yieldingly forced into contact with the work support and any suitable mechanism may be provided for raising the same.

My feeding mechanism comprises in the present embodiment of my invention, two feed dogs 13 and 14. The feed dog 13 is provided with downwardly extending lugs

15 and 16, which engage loosely a rod 17 mounted to slide in suitable bearings in the work support 1.

The feed member 14, is provided also with 5 downwardly extending lugs 18 and 19, which engage loosely a rod 20, also mounted to slide freely in bearings in the work support.

A block 21 engages both rods 17 and 20 between the depending lugs of the respective 10 feed dogs and is secured to each of said rods by a suitable screw. Said block 21 holds the feed dogs from movement longitudinally of their supporting rods, but allows said feed dogs to swing about said rods as a 15 pivotal support. The block 21 is provided with a projecting pin or roller 22, which lies in the forked end 23 of an arm 24, secured to the outer end of a shaft 25. The shaft 25, is oscillated by any suitable mechanism, 20 and as said shaft oscillates, the rods 17 and 20 will be reciprocated back and forth in their supporting bearings.

The lug 15 on the feed dog 13, is extended downwardly and carries a laterally extending roller 26. The lug 19 on the feed dog 14 is also extended downwardly and carries a laterally extending roller 27.

The shaft 28 located in the work support, carries at its forward end a laterally extending arm 29, which is provided with a 30 V-shaped disk 30. Said V-shaped disk 30, extends between the rollers 26 and 27, carried by the feed dogs 13 and 14.

As the shaft 28 is oscillated, the disk 30 is 35 raised or lowered and as the V-shaped portion of said disk is forced against the rollers 26 and 27, the feed dogs 13 and 14 are oscillated upon their pivotal support, thus forcing the feed engaging surface of said feed 40 dogs, outward through the work support, into engagement with the material.

A suitable spring 31 is secured to the feed dogs 13 and 14 at a point above their pivotal support and normally tends to hold said 45 feed dogs beneath the work support.

The operation of my improved feeding mechanism will be obvious from the above description. The work is laid upon the work support and drawn across the apex of the 50 work supporting members 2 and 3, thus crimping the work for the entrance of the needle, so that said needle may enter and emerge from the same surface of the work.

The work is held upon the crimping ridge 55 by the presser feet 9 and 10. As the shaft 28 is oscillated, the disk 30 is brought into contact with the lower ends of the feed dogs and as the said lower ends of the feed dogs are separated, the feeding surfaces of the 60 feed dogs are forced out through the slots in the work supporting members 2 and 3, into engagement with the work or material resting thereon.

The shaft 25 is now oscillated through the 65 arm 22 and its forked connection with the

block 21 reciprocates the feed dogs longitudinally of the work support, thus carrying the material to position the same for the next stitch. The feed dogs are now withdrawn by the spring 31 beneath the work 70 supporting members 2 and 3, and the reverse oscillation of the shaft 25 carries said feed dogs back to their initial position.

It will be noted that the feed dogs as they move through the work supporting members 75 are moving substantially in a direction at right angles to the said work supporting members, or if anything in a direction away from the apex of the crimping member, and therefore the work or material which is on 80 the crimping member, is held in its stretched condition.

In the modified form of my invention shown in Figs. 5 to 7 inclusive, the feed dogs 85 31 and 32 are provided with intermeshing gears 33, whereby all movements of either feed dog toward and from each other are so communicated to the other. The feed dog 31, is secured to its supporting rod by a set screw 33, so that said feed dog and supporting rod will oscillate together. The feed dog 32 is similarly secured to its supporting rod. The block 34, which engages the supporting rods of the feed dogs for the purpose of giving the feed dogs their longitudinal movement, is loosely connected to each of said rods, so that said rods may be oscillated in said supporting block. 95

The supporting block 34 carries a projecting roller which engages the forked end of 100 the arm 22 carried by the shaft 25. An arm 35 is mounted upon the rod 20 and has an upwardly extending portion which is secured to the feed dog 32 by a suitable pin 36. Said arm 35 at its lower end carries a 105 ball stud 37 which is connected by means of a link 38 to a ball stud 40 threaded into an arm 41 mounted on the outer end of the shaft 28.

As the shaft 28 is oscillated, the arm 35 110 through the link 38 oscillates the feed dog 32, and through the intermeshing feed gear 36 oscillates the feed dog 31. The feeding mechanism shown in my modified form of construction, operates practically in the 115 same manner as the feeding mechanism above described, except that all the movements of the feed dogs are positive.

Having thus particularly described my invention, what I claim as new and desire to secure by Letters Patent, is:—

1. The combination with a work support having oppositely inclined work supporting surfaces forming a crimping ridge, presser members co-operating therewith, of feeding 120 mechanism including feed dogs, operating through each of said work supporting surfaces, means for moving said feed dogs to feed the material and means for giving each of said feed dogs a fabric engaging move- 130

ment in a direction at an angle to a central plane passing through said ridge, and in a direction substantially at right angles to the work supporting surface, through which said feed dogs operate.

2. The combination with a work support having oppositely inclined work supporting surfaces forming a crimping ridge, presser members co-operating therewith, of a feeding mechanism including feed dogs located beneath said inclined work supporting surfaces and having work engaging movements in a direction at an angle to a central plane passing through said ridge and in a direction substantially at right angles to the supporting surfaces through which said feed dogs operate, and means for simultaneously moving said feed dogs to feed the fabric.

3. The combination with a work support having oppositely inclined work supporting surfaces, feed dogs pivoted beneath said work support, means for swinging said feed dogs about their pivotal supports to give thereto a fabric engaging movement, means for moving said feed dogs to feed the fabric, said pivotal supports of said feed dogs being so disposed relative to the work supporting surfaces, that said feed dogs will move substantially in a direction at right angles to the supporting surfaces through which said feed dogs operate and in a direction at right angles to the feed of the fabric.

4. The combination with a work support having inclined work supporting surfaces of a feeding mechanism including a feed dog pivoted beneath said work support, means for swinging said feed dog about its pivotal center to give thereto a fabric engaging movement, means for moving said feed dog to feed the fabric, said pivotal center of said feed dog being so disposed relative to the work support that said feed dog moves in a direction substantially at right angles to the work supporting surface through which it passes, when brought into engagement with the fabric.

5. The combination with a work support, of a feeding mechanism including pivotally supported feed dogs, members on which said feed dogs are pivoted, means for oscillating said feed dogs on said members in opposite directions and means for moving said members longitudinally to give said feed dogs a work feeding movement.

6. The combination with a work support, of a feeding mechanism including spaced rods sliding in bearings in said work support, a feed dog pivoted on each of said rods, means for swinging said feed dogs laterally away from each other to give thereto a fabric engaging movement and means for moving said rods longitudinally to feed the fabric.

7. The combination with a work support, of a feeding mechanism including pivoted

feed dogs, a shaft mounted in said work support having oscillation, devices between said shaft and said feed dogs for moving the same to feed the fabric, and a second shaft located in said work support for oscillation and devices between said second shaft and said feed dogs for giving thereto a fabric engaging movement.

8. The combination with a work support, of a feeding mechanism, including spaced rods mounted to slide in said work support, a feed dog carried by each of said rods, a shaft located in said work support and devices between said shaft and said spaced rods for moving said rods longitudinally, a second shaft mounted in said work support, and devices between said shaft and said feed dogs for moving the same in opposite directions.

9. A sewing machine including in combination a work support having surfaces constituting a ridge forming member, each of said surfaces having openings therethrough for a feed dog, an overhanging arm, a needle mounted on said overhanging arm and moving across said ridge forming member, and a feeding mechanism located beneath the said ridge forming member, said feeding mechanism including positively moving feed dogs operating respectively in said openings and movable in a direction substantially at right angles to said surfaces when engaging the fabric, and means for giving said feed dogs a fabric feeding movement.

10. A sewing machine including in combination a work support, having a ridge forming member, an overhanging arm, a needle mounted on said overhanging arm, a feeding mechanism comprising supporting rods mounted in said work support, feed dogs carried by said supporting rods, means for moving said supporting rods longitudinally to give said feed dogs a fabric feeding movement and means for swinging said feed dogs laterally away from each other upon said rods to bring the same into engagement with the fabric.

11. A sewing machine including in combination a work support, having a ridge forming member, an overhanging arm, a needle mounted on said overhanging arm, feeding mechanism comprising supporting rods mounted to slide in said work support, a feed dog pivoted upon each of said supporting rods, means for moving said supporting rods to feed the fabric and means for moving said feed dogs simultaneously in opposite directions to engage the fabric.

12. A sewing machine including in combination, a work support, an overhanging arm, oppositely inclined work supporting members over which the fabric may be crimped, a needle carried by said overhanging arm, and moving across the crimping members, and a feeding mechanism com-

prising supporting rods located beneath said work supporting members, feed dogs carried by said supporting rods, means for moving said feed dogs to give said fabric a feeding movement, and devices for moving said feed dogs in opposite directions to engage the fabric.

13. A sewing machine including in combination, a work support, an overhanging arm, oppositely inclined work supporting members over which the fabric may be crimped, a needle carried by said overhanging arm, and moving across the crimping members, and a feeding mechanism comprising supporting rods located beneath said work supporting members, feed dogs carried by said supporting rods, means for moving said feed dogs to give said fabric a feeding movement, a shaft mounted in said work support for oscillation, a cam disk carried by said shaft and engaging said feed dogs for moving the same in opposite directions to engage the fabric.

14. A feeding mechanism including in combination supporting rods, a feed dog pivoted upon each rod and having a downwardly extending member, means for moving said supporting rods longitudinally and means for engaging the downwardly extending portions of said feed dogs for swinging the same upon said rods.

15. A feeding mechanism including in combination, supporting rods, a feed dog pivoted upon each rod and having a downwardly extending portion, means for moving said rods longitudinally, an oscillating shaft, a cam disk carried thereby and engaging the downwardly extending portions of said feed dogs for moving the same in opposite directions and a spring for holding said feed dogs in contact with said cam disk.

16. A feeding mechanism including in combination a work support, a feed dog having spaced perforated lugs, a supporting rod extending through said perforated lugs and mounted in bearings in said work support, a block mounted on said rod and located between said lugs, devices for engaging said block for moving said feed dog laterally and means for swinging said feed dog upon said rod.

17. A feeding mechanism including in combination, a work support, a feed dog having spaced perforated lugs, a supporting rod extending through said perforated lugs and mounted in bearings in said work support, a block mounted on said rod and located between said lugs, devices for engaging said block for moving said feed dog laterally, one of said lugs having a downwardly extending portion carrying a roller, an oscillating shaft having a cam disk operating against said roller to oscillate the feed

dog, and a spring for holding said feed dog in contact with said cam disk.

18. The combination of a work support, having inclined work supporting surfaces forming a crimping ridge, feeding members, and means for moving each of said feeding members toward and from the material in a direction substantially at right angles to said inclined work supporting surfaces and in a direction at an angle to a central plane passing through said ridge.

19. A sewing machine including in combination, a work support, stitch-forming mechanism including a needle, and a feeding mechanism, said feeding mechanism including feed dogs located beneath said work support, means for moving said feed dogs simultaneously and intermittently into engagement with the fabric, and toward and from each other during each reciprocation of the needle, and means for moving said feed dogs to feed the fabric, said feed dogs being moved from each other while in engagement with the fabric for stretching the same.

20. In a sewing machine, a crimping device, a compound feeding device having members located upon opposite sides of the crimping ridge, means for moving said members toward and from each other, whereby the fabric is drawn taut, and means for moving said members to carry the fabric forward over the crimping ridge.

21. In a sewing machine, a crimping ridge, a feeding device, comprising feeding members located upon opposite sides of the crimping ridge, means for moving said feeding members toward and from the fabric, and away from each other after engaging the fabric, in order to stretch the fabric taut over the crimping ridge, and means for moving the feeding members to feed the fabric.

22. A sewing machine including in combination, a work support, stitch-forming mechanism, a feeding mechanism including an operating shaft, feed dogs both of which are located at one side of the work support, and means operated by said shaft for moving said feed dogs simultaneously and intermittently into engagement with the fabric and toward and from each other, and for moving said feed dogs to feed the fabric, said feed dogs being moved from each other while in engagement with the fabric for stretching the same.

In testimony whereof I affix my signature, in presence of two witnesses.
